UNITED STATES PATENT OFFICE.

HARRY M. RAND, OF WESTVILLE, NEW JERSEY.

VALVE-GRINDER.

1,328,197.

Specification of Letters Patent. Patented Jan. 13, 1920.

Application filed June 3, 1919. Serial No. 301,400.

To all whom it may concern:

Be it known, that I, HARRY M. RAND, a citizen of the United States of America, residing at Westville, in the county of 5 Gloucester and State of New Jersey, have invented new and useful Improvements in Valve-Grinders, of which the following is a specification.

This invention relates to valve grinding tools, particularly to a tool designed for use 10 in grinding the valves of an extremely popular make of motor vehicle engine, and has for its object the provision of a valve grinding tool engageable upon a valve stem 15 whereby the same may be rotated back and forth, instead of engaging the head of the valve, as is the ordinary practice, the advantage being that working from below the head the operator may lift the valve from its 20 seat partially from time to time to permit fresh valve grinding compound to flow onto the surface being ground.

An important and more specific object is 25 the provision of a tool of this character comprising a handle from which extends a clamping member engageable about the valve stem and from which also extends a member adapted to be passed through the hole in the 30 valve stem from which the valve spring retaining pin has previously been removed.

An additional object is the provision of a device of this character which will be extremely simple and inexpensive in manufacture, which is easy to operate, which will be 35 efficient and durable in use, and a general improvement in the art.

With the above and other objects and advantages in view, the invention consists in the details of construction to be hereinafter 40 more fully described and claimed, and illustrated in the accompanying drawing, in which—

Figure 1 is a side elevation of my device showing it in engagement with a valve stem, 45 and

Fig. 2 is a plan view, the valve stem being shown in section.

Referring more particularly to the drawing, the letter A designates a valve of the 50 type used in the Ford automobile engine, this valve including a stem B through which is formed a hole C within which is engaged the valve spring retaining pin, not shown. The valve is illustrated for the sake of clear-

ness in explaining the construction and operation of my device, though it of course forms no part of the invention.

My device comprises a handle 10 which may be of any suitable material, preferably wood, and from one end of which extends 55 a pair of clamping arms 11 curved for engagement with the valve stem B and terminating at their outer ends in outwardly directed points 12 forming an enlarged entrance opening. The clamping members 11 60 are formed from spring material which may conveniently be piano wire and the wires are twisted together, as shown at 13, and inserted within the handle 10. Also twisted with the wires forming the clamping members 11 65 is a similar wire 14 which extends in spaced parallel relation to the clamping members 11 and which is adapted for insertion through the hole C in the valve stem. An enlargement or stop collar 15 is provided on 70 the wire 14 for limiting its passage through the hole C.

In the use of the device, the valve spring and its retaining pin, not shown, having been first removed from the valve, the operator grasps the handle 10 and inserts the end of the wire 14 through the hole C in the valve stem and engages the clamping members 11 upon the valve stem. It will be observed that the wire 14 is of greater length 80 than the clamping members 11 so as to facilitate its insertion within the hole C before the clamping members 11 engage the stem. The tool being thus positioned, the operator pulls upwardly upon the handle 85 10 and consequently elevates the valve A from its seat so that the proper valve grinding compound or the like may be placed upon the seat or upon the edge of the valve. The operator then presses downwardly 90 upon the tool to reseat the valve and then he rocks the valve back and forth by swinging the handle 10 laterally. During the above described rocking movement, it is advisable, as is well known, that the operator 100 raise the valve a trifle from time to time to permit the valve grinding compound to flow onto the surfaces being ground. If necessary, pressure may be placed upon the valve by means of a punch or the like, 105 though it will be found sufficient for practical purposes that the operator merely press downwardly upon the tool.

2
From the foregoing description and a study of the drawing, it will be apparent that I have thus provided an extremely simple and inexpensive tool whereby valves 5 may be ground easily and expeditiously and in a highly efficient manner.

While I have shown and described the preferred embodiment of my invention, it is of course to be understood that I reserve the 10 right to make such changes in the form, construction, and arrangement of parts as will not depart from the spirit of the invention or the scope of the subjoined claims.

Having thus described my invention, I 15 claim:—

1. A valve grinding tool comprising a handle, a pair of spring arms extending from one end of said handle and adapted for resilient gripping engagement upon the 20 stem of a valve, and a member extending from the same end of the handle in spaced relation to said clamping arms and adapted for insertion within the valve spring pin-hole in the stem.
2. A valve grinding tool comprising a handle, a clamping member extending from one end of said handle and including spring arms engageable upon a valve stem, and a member extending from the same end of 30 said handle in spaced parallel relation to

said clamping member and engageable within the valve spring pin hole in the stem.

3. A valve grinding tool comprising a handle, a pair of spring arms twisted together and extending from one end of said handle and adapted for partial embracing engagement with a valve stem, and a member twisted about said spring arms adjacent their juncture with the handle and extending in spaced parallel relation to said 40 spring arms and engageable through the valve spring pin hole in the stem, said member being of greater length than said spring arms and being provided with an enlarged portion serving as a stop for limiting the 45 passage of said member through said hole.

4. A valve grinding tool comprising a handle, a resilient clamping member extending from one end of said handle and engageable about a valve stem, and a member extending from the same end of said handle in spaced relation to said clamping member and extending beyond the clamping member and adapted for engagement within the valve spring pin-hole of a valve stem, 50 said member having a projection thereon limiting its degree of insertion within the pin-hole.

In testimony whereof I affix my signature.
HARRY M. RAND.
